UNITED STATES PATENT OFFICE.

JAMES CLARENCE BELL, OF MURRAYVILLE, ILLINOIS, ASSIGNOR OF ONE-HALF TO
ROY CLARK, OF MURRAYVILLE, ILLINOIS.

MEANS FOR HOLDING CORSET STAYS IN PLACE.

1,421,121.

Specification of Letters Patent. Patented June 27, 1922.

Application filed July 26, 1920. Serial No. 399,011.

To all whom it may concern:

Be it known that I, JAMES CLARENCE BELL, a citizen of the United States, residing at Murrayville, in the county of Morgan and 5 State of Illinois, have invented certain new and useful Improvements in Means for Holding Corset Stays in Place, of which the following is a specification.

This invention relates to corset structures 10 and the primary object of the invention is to generally improve the steel structure utilized for the frame work of the corset.

One of the objects of the invention is to provide a main stay to which the corset stays 15 are attached whereby relative independent movement of the parallel corset stays will be prevented and thus prevent the stays from protruding through the marginal portions of the corset.

20 Another object of the invention is to provide a rigid structure for maintaining the corset stays in proper relative positions so that the ends of the stays will be prevented from protruding through the fabric from 25 which the corset is made and which will also be arranged so that the desired flexibility will be secured.

Other objects of the invention will appear 30 upon consideration of the following detail 35 description and accompanying drawings, wherein:—

Figure 1 is an elevation of a part of the corset structure included in the invention, showing one half of the frame work.

35 Figure 2 is a detail perspective view of two of the stays illustrating a modified form of connecting the stays.

Figure 3 is a perspective view of a single stay having one of the stop members attached 40 thereto.

Figure 4 is a detail cross section taken approximately on the line 4—4 of Fig. 1.

Figure 5 is a plan view showing the complete structure.

45 Referring to the drawings by numerals, and particularly to Fig. 1 wherein one half of the corset structure is illustrated, the front stay 1 is connected to one end of a main stay 2 which is in the form of a metallic flexible 50 band riveted as indicated at 3 to secure one end of the main stay 2 to the front stay 1. This main stay 2 is adapted to extend entirely around the frame structure and consequently its opposite end is secured in the

same manner to the other front stay which 55 will be similar to the stay indicated by the numeral 1. A plurality of parallel stays of the usual formation are attached to the main stay 2 and as shown in Fig. 1, a plurality of the widest stays designated at 4 form the 60 back portion of the frame structure and are secured by rivets 5 to the main stay 2. A plurality of pairs of narrow stays 6 are attached to the main stay 2 between the stays 4 and the front stay 1 to form the front structure 65 of the corset frame work. These stays 6 are narrow to provide the proper coefficient of flexibility and are arranged in pairs to give the desired strength to the structure. Each of the stays is secured by the rivets 5 70 which extend through the stay and the main stay 2 and also through a washer 7. The washers are provided to give strength to the portions through which the rivets extend so that breaking will be prevented. 75

In Fig. 2 I have illustrated the manner in which two, three or four or a greater number of stays may be fastened together by the main stay 2' which has its ends riveted as indicated at 8 to the stay. In Fig. 3 a single 80 stay 9 is provided with a main stay or stop member 10 riveted as indicated at 11 so that the ends of the member 10 project from opposite edges of the stay 9. When the structure is secured in the fabric or material from 85 which the corset is constructed, and securely stitched in the usual manner, the mainstay will prevent the independent movement of the parallel stays so that none of them can move independently of the others. The stays 90 therefore can not protrude through the marginal portions of the fabric and the life of the corset will be materially increased.

The above description includes the preferred embodiment of the invention, but I 95 desire it to be understood that I may make such changes in the details of construction as fall within the spirit of the invention and the scope of the claims hereunto appended.

What I claim is:—

1. A corset structure comprising a plurality of parallel stays, and a main stay disposed at right angles to the parallel stays and rigidly fixed thereto to prevent independent relative movement of the parallel 105 stays with respect to each other, all of the said stays being connected to the said main stay at different points intermediate the ends 100.

of the said parallel stays whereby the opposite ends of the parallel stays will be held in irregular alinement.

2. A corset structure comprising a plurality of parallel stays, certain of the stays at the front of the corset being narrower and arranged in pairs to provide an inherent resiliency and the desired rigidity, the other stays at the back of the structure being wider, a main stay extending around the structure and riveted to all of the said parallel stays.

3. A corset structure of the character described comprising a flexible steel main stay, front stays fixed to the terminals of the main stay, a plurality of parallel stays, certain of the said stays being secured to the main stay to form the back of the structure, the other of the stays being narrower and arranged

in parallel pairs, rivets to secure all of the stays to the main stay and washers carried by the rivets and engaged with the parallel stays at the sides opposite to the main stay.

4. A corset structure of the character described comprising a flexible steel main stay, front stays fixed to the terminals of the main stay, a plurality of parallel stays, fixed to the said main stay at different points intermediate the ends of the said main stay and of varying lengths, certain of the said stays being secured at one end portion of the main stay to form the back of the corset structure, the other stays being narrower and arranged in parallel relation at the opposite end portion of the main stay to form the front corset structure.

In testimony whereof I affix my signature.

JAMES CLARENCE BELL.
